UNITED STATES PATENT OFFICE

JOHN F. SCHYLANDER, OF CHICAGO, ILLINOIS

PAINT SPRAYER

Application filed December 17, 1928. Serial No. 326,627.

My invention relates to sprays of the general type described and claimed in my co-pending applications, Serial Nos. 310,776, filed October 6, 1928, and 312,057, filed October 12, 1928. The invention has to do particularly with devices for producing a spray of finely atomized liquid material such as paint or other pigment, disinfectant, fungicides and insecticides, finely divided powdered material, etc.

An object of my invention is to provide a device for producing a spray of material in a quantity variable at the will of an operator and for any desired length of time, with slight effort on the part of the operator.

A further object is to provide a device of the class described which will consist of a small number of relatively simple parts, the device being inexpensive to manufacture, rugged, and easy to operate.

Many other objects and advantages of the construction herein shown and described, will be obvious to those skilled in the art from the disclosure herein given.

To this end my invention consists in the novel construction, arrangement and combination of parts herein shown and described, and more particularly pointed out in the claims.

Referring now to the drawings forming a part of this specification and illustrating a preferred embodiment of my invention:

Fig. 1 is a sectional view through a device embodying my invention mounted on a container, the latter being shown fragmentarily;

Fig. 2 is a sectional view taken on the line 2-2 of Fig. 1;

Fig. 3 is a sectional view taken on the line 3-3 of Fig. 1; and

Fig. 4 is a sectional view on an enlarged scale taken on the line 4-4 of Fig. 1.

In the particular preferred embodiment shown in the drawings, the numeral 10 indicates a container of any desired shape, size, and material for holding the liquid or powder which is to be sprayed. This container has a neck 12 which is preferably cylindrical and may be exteriorly threaded to engage a threaded portion 13 of a cap member 14. The cap member is preferably

formed of sheet metal or the like and has secured to the upper portion thereof preferably by solder or other suitable means, a tubular member 15. This tubular member is open at one end, as at 16, and its opposite end 17 is closed, save for an aperture 18. The closed end 17 is peculiarly shaped, as shown in Figs. 1 and 3 and may best be described by saying that this end of the tubular member is first formed in a hemispherical shape and is then given a diametrical crease, as shown at 20. As a result, the aperture 18, originally circular is substantially elliptical and extends in a substantially V-shaped manner as shown in Fig. 1. The top portion of the cap 14 is apertured as at 21, 22 and 23, while apertures are provided in the bottom of the tubular member 15 aligned with the apertures of the cap. Through the aperture 21 slidably extends a tubular member 25 having an end 26 disposed substantially at right angles to the portion which depends into the container 10 with room for vertical movement as hereinafter described.

Secured to the tubular member 25 by means of solder or other suitable means is an arm 28 carried by a rod 29. The rod 29 extends through the aperture 22 of the cap and aligned aperture of the tubular member 15 and carries at its end a manipulating member 35 having a knurled head 36 with an annular shoulder 36' (Fig. 4), the manipulating member passing through an aperture 37 provided in the tubular member 15. As best shown in Fig. 4, the end of the rod 29 is threaded as at 38, engaging female threads 38' in the manipulating member 35. The rod 29 has a pair of longitudinal and diametrical keyways 30 engageable in opposed slots 31 in the wall of the aperture 22, and the rod 29 is thus prevented from turning on its longitudinal axis. The manipulating member has an annular shoulder 40, and a helical compression spring 42 is disposed around the rod 29, abutting at one end against the shoulder 40 and at the other against the interior of the tubular member 15, so that the tendency thereof is to maintain the manipulating member and the tubular member 25 in extreme elevated position.

In operation, the tubular member 15 is connected to a suitable conduit 45 leading from any convenient source of air pressure (not shown). Such source of pressure may be a vacuum cleaner operating as a blower, an air pump, or a compressed air reservoir. In the normal condition of the device, as indicated by the dotted lines in Fig. 1, air entering the tubular member 15 from the conduit 45 will pass, for the most part, directly through the tubular member 15 and out through the aperture 18, a small amount of air passing through the aperture 23 into the container 10. Some of the air passing directly through the member 15 tends to exert a back pressure through the end of the tube 25. Under such conditions, the device will be inoperative and no material will issue from the tubular member 25.

When, however, it is desired to produce a spray, the manipulating member 35 is manually depressed against the action of the spring 42. This manipulating member carries with it the tubular member 25, the outlet end 26 of which is brought into registry with the V-shaped aperture 18. As the end of the tubular member 25 approaches the aperture 18, the air issuing through said aperture will tend to produce a suction or vacuum within the end of the tubular member, which suction, assisted by the pressure of air within the container 10 which has entered through the aperture 23, will tend to cause the material within the container to be forced up through the tube 25 and out of the end thereof. Inasmuch as the current of air passing out through the V-shaped aperture 18 is moving at an extremely high velocity and is caused to diverge by the edges of the V-shaped aperture, the material being emitted from the end of the tubular member 25 will tend to issue therefrom as a more or less conically shaped cloud. As the end 26 of the tubular member 25 approaches the center of the V-shaped aperture, the vacuum induced in the end thereof will become stronger, so that the volume of spray will increase. The maximum spray will be produced when the outlet end of the tube 25 is in exact registry with the aperture 18 as shown in full lines in Fig. 1. Hence, it is apparent that the amount of material issuing from the device may be regulated by varying the amount which the manipulating member is depressed.

The maximum limit of the quantity of spray issuing from the device may be fixed by adjustment of the manipulating member 35. This is accomplished merely by turning the manipulating member on the threaded end of the rod 29. This results in either shortening or increasing the distance which the tubular member 25 may be depressed, inasmuch as the downward movement of the manipulating member is limited by the abut-

ment of the shoulder 36' against the top of the tubular member 15.

The tubular member 25 may easily be cleaned merely by insertion of a pipe cleaner therein.

The device is very easily carried to any point where the spray is desired, the conduit 45 usually being flexible. The tubular member 15 may, if desired, be used as a handle and the manipulating member displaced by the thumb, thus leaving the other hand free.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the class described, an air conduit having an inlet opening and an outlet opening, a material conduit having an outlet portion whose axis is parallel to that of said air conduit, said outlet portion extending towards said outlet opening, manually operable means for moving said outlet portion transversely of its axis so as to bring its outlet into registry with that of said air conduit, adjustable means for limiting the movement of said manually operable means so as to control the maximum volume of material issuing from said device, and means for resiliently retaining said outlet portion out of registry with the outlet opening of said air conduit so that said device will be normally functionally inoperative.

2. In a device of the class described, an air conduit having an inlet opening, the opposite end of said conduit having an inwardly extending wall with an outlet opening therein, a material conduit having an outlet portion whose axis is parallel to that of said air conduit, said outlet portion extending towards said outlet opening, manually operable means for moving said outlet portion transversely of its axis so as to bring its outlet into registry with that of said air conduit, adjustable means for limiting the movement of said manually operable means so as to control the maximum volume of material issuing from said device, and means for resiliently retaining said outlet portion out of registry with the outlet opening of said air conduit so that said device will be normally functionally inoperative.

3. In a device of the class described, an air conduit having an inlet opening, the opposite end of said conduit having an inwardly extending wall with a substantially elliptical aperture, a material conduit having an outlet portion whose axis is parallel to that of said air conduit, said outlet portion extending towards said aperture, manually operable

means for moving said outlet portion transversely of its axis and parallel to the major axis of said elliptical aperture so as to bring its outlet into substantial registry with said aperture, adjustable means for limiting the movement of said manually operable means so as to control the maximum volume of material issuing from said device, and means for resiliently retaining said outlet portion out 10 of registry with said aperture so that said device will be normally functionally inoperative.

4. In a device of the class described and in combination with closure means for a container, an air conduit having an inlet opening, the opposite end of said conduit having an inwardly extending wall with an outlet opening therein, a material conduit having a portion adapted to extend into said 15 container and having an outlet portion extending towards said outlet opening and disposed substantially at right angles to the first named portion, and manually operable means for moving said material conduit 20 along the axis of the portion extending into said container, so as to bring its outlet into substantial registry with that of said air conduit.

5. In a device of the class described and in combination with closure means for a container, an air conduit having an inlet opening, the opposite end of said conduit having an inwardly extending wall with a substantially elliptical aperture, a material conduit 25 having a portion adapted to extend into said container and having an outlet portion extending towards said aperture and disposed substantially at right angles to the first named portion, and manually operable means 30 for moving said material conduit along the axis of the portion extending into said container so as to bring its outlet into substantial registry with said aperture.

6. In a device of the class described, and in combination with closure means for a container, an air conduit having an inlet opening, the opposite end of said conduit having an inwardly extending wall with an outlet opening therein, a material conduit having 35 a portion adapted to extend into said container and having an outlet portion extending towards said outlet opening and disposed substantially at right angles to the first named portion, manually operable means for moving said material conduit along the axis of the portion extending into said container so as to bring its outlet into substantial registry with said aperture, and means for limiting the movement of said manually operable means so as to control the maximum volume of material issuing from said device.

7. In a device of the class described and in combination with closure means for a container, an air conduit having an inlet opening, the opposite end of said conduit having

an inwardly extending wall with a substantially elliptical aperture, a material conduit having a portion adapted to extend into said container and having an outlet portion extending towards said aperture and disposed substantially at right angles to the first named portion, manually operable means for moving said material conduit along the axis of the portion extending into said container so as to bring its outlet into substantial registry with said aperture, and adjustable means for limiting the movement of said manually operable means so as to control the maximum volume of material issuing from said device.

8. In a device of the class described, and a combination with closure means for a container, an air conduit having an inlet opening, the opposite end of said conduit having an inwardly extending wall with an outlet opening therein, a material conduit having a portion adapted to extend into said container and having an outlet portion extending towards said outlet opening and disposed substantially at right angles to the first named portion, manually operable means for moving said material conduit along the axis of the portion extending into said container so as to bring its outlet into substantial registry with said aperture, adjustable means for limiting the movement of said manually operable means so as to control the maximum volume of material issuing from said device, and means for resiliently retaining said outlet portion out of registry with said aperture so that said device will be normally functionally inoperative.

9. In a device of the class described and in combination with closure means for a container, an air conduit having an inlet opening, the opposite end of said conduit having an inwardly extending wall with a substantially elliptical aperture, a material conduit having a portion adapted to extend into said container and having an outlet portion extending towards said aperture and disposed substantially at right angles to the first named portion, manually operable means for moving said material conduit along the axis of the portion extending into said container so as to bring its outlet into substantial registry with said aperture, adjustable means for limiting the movement of said manually operable means so as to control the maximum volume of material issuing from said device, and means for resiliently urging said outlet portion out of registry with said aperture so that said device will be normally functionally inoperative.

In witness whereof I hereunto subscribe my name this 30th day of November A. D., 1928.

JOHN F. SCHYLANDER.
